APPARATUS FOR ROASTING ORE

Kenneth D. McBean, Trail, British Columbia, Canada, assignor to The Consolidated Mining and Smelting Company of Canada, Limited, Montreal, Quebec, Canada, a corporation of Canada

Application October 28, 1947, Serial No. 782,618

4 Claims. (Cl. 266—20)

1

This invention relates to an apparatus for roasting ore and concentrates and is particularly directed to the roasting of mineral sulphides in gaseous suspension.

Methods and apparatus for roasting mineral sulphides in gaseous suspension are well known and are in relatively wide spread use. In general, the methods involve blowing a mixture of finely divided, dried mineral sulphide ore or concentrate particles into the upper part of a combustion chamber maintained by the heat of the combustion of the particles at a relatively high temperature, wherein the particles are disseminated concurrently with the air blast through it for the exposure of the surfaces of each particle to the oxidizing action of the hot combustion gases. The conversion of the sulphides to oxides is effected by the combustion of the sulphur content of the charge supported by the air of the blast. The roasting temperature and the time of retention of the particles in the combustion zone are regulated in such a manner as to promote the oxidation of the charge without fusion or incipient fusion. The roasted material settling at the bottom of the combustion chamber is removed for further processing and the gaseous products of combustion are exhausted from the combustion chamber having a high concentration of sulphur dioxide. Such methods and apparatus are disclosed in U. S. Patent No. 1,884,348 and No. 1,963,282.

In roasting mineral sulphide particles in gaseous suspension according to known methods and apparatus, the sulphide particles have been dried on drying hearths placed above the combustion chamber or in separate drying apparatus outside the roasting furnace.

An important object of the present invention is to provide an improved apparatus for roasting mineral sulphides in gaseous suspension whereby the productive capacity of the roasting furnace is substantially increased with a substantial decrease in capital and operating costs.

A further important object of the invention is to provide an improved roasting furnace which permits the arrangement of the apparatus associated with the roasting furnace, such as the feed bins, fans, conduits and conveyors, at a low level, preferably adjacent to the floor level, which reduces the amount of heavy supporting structural steel required, and centralizes adjacent to that level the control of the process.

A further important object is to provide a novel design of roasting furnace which may be readily modified to increase the capacity of the furnace. This may be accomplished by merely extending

2

the combustion chamber and burners upwardly without extensive dismantling and rearrangement of the furnace and associated parts.

An understanding of the manner in which the above and other objects of the invention are attained may be had from the following description, reference being made to the accompanying drawings in which:

Figure 1 is a plan view illustrating schematically a preferred arrangement of the furnace and associated apparatus;

Figure 2 is a plan view in section taken along the line 2—2 of Figure 6;

Figure 3 is a plan view in section taken along the line 3—3 of Figure 6;

Figure 4 is a plan view in section taken along the line 4—4 of Figure 6;

Figure 5 is a plan view in section taken along the line 5—5 of Figure 6;

Figure 6 is a front elevation in section of a roasting furnace embodying features of the present invention;

Figure 7 is a side elevation illustrating a preferred arrangement for distributing dried ore particles to the burners;

Figure 8 is a side elevation illustrating a preferred arrangement of the roasting furnace and associated storing and feeding apparatus; and

Figure 9 is a side elevation in section of the roasting furnace illustrating a preferred arrangement of conduits from the roasting chamber to the drying hearth and from the drying hearth to the intake of the burner fan.

Like reference characters refer to like parts throughout the specification and drawings.

A preferred embodiment of the invention is illustrated in Figures 1 to 9 inclusive and comprises, in general, a roasting furnace indicated by the numeral 20, a grinding mill 21, such as a ball mill, for pulverizing the ore to a high degree of fineness, a classifier 22 for classifying the pulverulent ore particles from the grinding mill, and a blower 61 for distributing the ore particles to the burners, and associated fans, conveyors, ducts and storage bins, all of which are described in detail hereinafter.

The roasting furnace 20 is preferably a vertically disposed, elongated cylindrical metal shell internally lined with heat insulating material 30, such as refractory bricks, capable of withstanding the high temperature corrosive and erosive actions of the gases and the particles to which it is subjected. The outer surface of the shell is also covered with insulating material 31, such as asbestos, to minimize heat losses through the shell.

The upper part of the furnace is in the form of an elongated, unobstructed combustion chamber 32 closed at the top by a steel cover 33 internally lined with refractory heat-insulating material, and at the bottom by the uppermost collecting hearth 34. The combustion chamber is of a height sufficient to permit the substantially complete oxidation of the particles as they fall to the uppermost collecting hearth 34 and of a diameter sufficient to permit the thorough dissemination of the particles therein.

The collecting hearths 34 and 36 and the drying hearth 36 are positioned in the lower part of the furnace below the combustion chamber. The uppermost collecting hearth slopes slightly upwardly from the shell of the furnace towards a centrally disposed shaft 37 to terminate short of the shaft to provide between the shaft and the rim of the hearth an annular drophole 38 leading to the lower hearth 35.

The lower hearth 35 is similar in construction to the upper hearth 34 and extends downwardly from a point adjacent to the shaft 37 to the inner lining of the furnace shell. An outlet drop-hole 39 is provided in the hearth 35 and extends through the furnace shell for the discharge from the furnace of roasted particles collected on the hearth 35.

The particles collected on the lower collecting hearth 35 are moved by rabbles 87 attached to rabble arms carried by the shaft towards the periphery of the furnace and into the discharge outlet 39 which extends to a storage bin (not shown).

The chamber formed between the upper collecting hearth 34 and the lower hearth 35 is provided with an outlet 82 in the furnace wall for the combustion gas. This outlet 82 is located at a convenient place opposite the discharge outlet 39. The combustion gases are withdrawn through outlet 82 and preferably passed through a waste-heat boiler and cyclone (not shown).

The drying hearth 36 is positioned below the lower collecting hearth 35. The drying chamber 25 is defined by the underside of the lower collecting hearth 35 and the top of the drying hearth 36 and is isolated from the collecting hearths except for such minor leakage of gas as may occur through the small space between the shaft and the lower collecting hearth. Hot combustion gases are withdrawn from the combustion chamber through the conduit 44, Figure 9, and passed into the drying chamber 25.

The shaft 37 is in the form of a hollow rotatable steel shell externally covered with refractory heat-insulating material. The shaft extends from a point below the furnace to terminate a short distance above the uppermost collecting hearth 34. Rabble arms 40, 41 and 42 are carried by the shaft and extend radially outwardly from the shaft to move, on rotation of the shaft, over the collecting hearths 34 and 35 and the drying hearth 36 respectively. The rabble arms are hollow and are adapted internally for cooling by a cooling medium, such as air, fed into the lower end of the shaft 37 through conduit 84 connected to a source of air under pressure, such as for example, a compressor (not shown) and discharged through conduit 85. The rabble arms are thus maintained at a temperature substantially below the normal operating temperature of the furnace. The shaft is rotated at a predetermined rate by means of a conventional driving mechanism 83, which may be a motor connected through a speed reduction gear box

to a pinion driving a ring gear mounted on the shaft below the furnace.

The associated parts of the roasting furnace for storing the moist ore, drying the ore, grinding the dried ore, delivering the finely comminuted, dried ore particles to the burners, and the circulation of combustion air and hot combustion gases are described hereinafter in conjunction with the operation of the furnace and its associated apparatus.

Moist sulphide ore particles are stored in the bin 50, and are fed, preferably at a predetermined rate, such as by a screw conveyor 51, to the periphery of the drying hearth 36.

15 The moist particles are advanced by the rabbles attached to the rabble arms 42, across the hearth 36 and during their passage across the hearth 36 the particles are exposed to the hot combustion gases fed into the drying chamber 25 from the combustion chamber 32 through the duct or conduit 44. The volume of the gas passing through the drying chamber 25 may be regulated such as by a valve 86, so that substantially all the moisture is removed by the time the particles have travelled across the hearth 36. The particles are moved toward and into the drop-hole 52, and into the conduit 53 which communicates with a conveyor 54. The conveyor 54 advances the dried particles to the grinding mill 21, such as a ball mill, wherein any agglomerations are broken up and any coarse particles are ground to a finely comminuted state.

The dried, comminuted particles are carried from the grinding mill 21 in an air current generated by a fan or blower 26 through conduit 55, through the classifier 22 to a separator 56, such as a cyclone separator, in which the air and the dried comminuted particles are separated. The air on losing its burden of ore particles is returned through conduit 57 by the blower 26 to the grinding mill 21. Any excess air from the grinding circuit is preferably fed from the blower 26 through vent 58 to the burner fan inlet 70 to be used in the combustion of the sulphide particles.

The dried ore particles are fed from the separator 56 through a conduit 60 to a dry feed storage bin 62, Figure 8. An air sealing valve 61 is provided in conduit 60.

50 The dried particles are fed at a predetermined rate by a conveyor 63 positioned below the storage bin 62. The conveyor 63 advances the ore particles to an air injector 64. The air injector 64 is connected to a source of high pressure air, such as a compressor (not shown) through conduit 65. The ore particles are carried in the air blast to the burner circuit.

The burner circuit preferably includes a conduit 66 connected at one end to a fan 67 and at 60 the other end to a junction 68 at which the stream of dried mineral sulphide particles and air is divided for distribution to the burners. An opening in the conduit 66 is provided for the injected stream of ore particles from the injector 64, as indicated by the numeral 69. Excess air from the grinding circuit may be returned through vent 58 to burner fan inlet 70.

Combustion gas is drawn through the drying chamber 25 and withdrawn through conduit 71 and returned through the burner fan inlet 73 to the combustion chamber 32. Atmospheric air for supporting oxidation, or combustion, of the sulphide particles is drawn into the burner circuit through the open end 72 of burner fan inlet 73.

The stream of combustion gases and suspended dried mineral sulphide particles is divided at junction 68, into substantially equal streams for delivery to the burners 74 and 75, each burner being supplied with approximately the same volume of the mixture of gas and sulphide particles.

In the preferred modification of the invention, two diametrically opposed burner nozzles 74 and 75 are extended angularly upwardly into the upper part of the furnace. The burner nozzles 74 and 75 are connected at their inlet ends to the conduits 76 and 77 respectively which, in turn, are connected to the junction 68. To ensure proper combustion of the particles and to avoid the formation of accretions on the furnace walls, the burner nozzles 74 and 75 are preferably directed angularly upwardly. If more than two burner nozzles are used in the furnace, these are preferably spaced equidistantly around the combustion chamber.

A scraper 80, carried by a stationary arm 81, preferably in the form of a water-cooled pipe, scrapes particles which have fallen on the top of the rotating shaft 37 and prevents their accumulation on the top of the shaft.

The burner fan 67 forces a mixture of air and combustion gas into the conduit 66 for circulation to the burner nozzles 74 and 75. Combustion gas is drawn from the combustion chamber through the conduit 44, and the drying chamber 25, and from the drying chamber through the conduit 71 to the burner inlet conduit 73 for admixture with atmospheric air and is delivered to the conduit 66 by fan 67. If desired, oxygen may be fed into the gas supplied to the burners to enrich the gas mixture. Additional air may be supplied to the burner circuit by by-passing air from the grinding circuit through conduit 58.

Hot combustion gases are withdrawn from the furnace through the outlet 82 in the furnace wall at a point adjacent to the periphery of the lower collecting hearth. The hot combustion gases withdrawn from the furnace are passed preferably through a heat exchanger, such as a waste-heat boiler, for the recovery of their heat value, and then passed through a separator, such as a cyclone separator, for the removal of the entrained solids.

The design of the furnace and the arrangement of the associated apparatus permit operation of the furnace to produce products of high quality at a high capacity.

In operation, the dried mineral sulphide particles, on being blown into the furnace, are rapidly dispersed in the hot combustion zone and quickly reach their ignition temperature. The roasted particles settle through the combustion chamber, on to the uppermost collecting hearth 34 whereon they are moved inwardly towards and into the annular drophole 38 to fall on to the lower collecting hearth 35. The particles on hearth 35 are rabbled outwardly towards and into conduit 39 through which they are removed from the furnace.

The rate of combustion and the temperature of the combustion chamber may be closely controlled by varying the rate of feed of mineral sulphide particles to the burner nozzles and the composition of the gaseous suspension medium, which may be easily varied by increasing or decreasing the rate of flow of atmospheric air or oxygen enriched air or combustion gases from the drying chamber or by returning cooled combustion gas from the exit of the heat exchanger.

The air or oxygen enriched air is introduced with the mineral sulphide particles fed to the burners 74 and 75 in the upper part of the furnace chamber. It is not necessary to introduce combustion air or oxygen elsewhere in the furnace.

The embodiment of the invention described in detail herein and illustrated in the drawings is capable of modification without departing from the scope of the invention. For example, in certain instances it may be desired to discharge all or part of the gas from the drying chamber to the atmosphere, or into the hot combustion gases passed to the heat exchanger, or into the gases discharged from the heat exchanger, rather than return it to the combustion chamber. Also, the gas from the drying chamber may be passed through a separator, such as a cyclone separator for the removal of the entrained solids. These entrained solids normally would include unroasted feed material, and this material is returned to the drying chamber. Also, if the wet feed material to the drying stage has a high moisture content, the number of drying hearths may be increased to ensure the substantially complete removal of the moisture before the feed material is discharged from the drying stage of the method.

The improved roasting furnace of the present invention offers a number of important advantages over the roasting furnaces of the prior art. By locating the drying hearth or hearths in the base of the furnace, the rotating shaft is extended only a short distance into the furnace leaving the combustion chamber free from any obstruction and thereby substantially increasing the capacity of the furnace. This design of furnace has a further important advantage in that it permits the thorough dispersion of the particles in the hottest zone of the furnace to promote thorough combustion at a rapid rate and at the same time enables a relatively high concentration of sulphur dioxide to be obtained in the exit gas and diminishes the formation of zinc ferrates when the furnace is employed for roasting zinc sulphides containing iron compounds.

Also, further increases in furnace capacity may be obtained by an easily erected upward extension of the furnace and burners without major dismantling and reconstruction operations.

The design of the furnace makes possible the concentration of apparatus associated with the furnace at or adjacent to the floor level with attendant substantial reduction in capital cost and important savings in operating costs and facilitates close control over the operation of the apparatus.

What I claim as new and desire to protect by Letters Patent of the United States is:

1. In a furnace for roasting mineral sulphides in gaseous suspension, a vertically elongated, unobstructed combustion chamber, an inlet for dried comminuted mineral sulphide particles in the upper part of said chamber, at least one collecting hearth below said combustion chamber, an outlet for roasted ore particles and an outlet for hot combustion gases from the collecting hearth, at least one drying hearth below the collecting hearth for drying the combustion chamber feed material, conduit means extending from the combustion chamber to a drying chamber defined by the collecting hearth and the drying hearth, an inlet for moist sulphide particles to the drying hearth, an outlet for dried sulphide particles from

the drying hearth, an outlet for gases from the drying chamber, means for conveying dried sulphide particles from the drying chamber to the combustion chamber, a rotatable shaft extending from a point below the furnace to terminate a short distance above the uppermost collecting hearth, rabble arms carried by said shaft, and rabbles carried by said arms adapted to move on said hearths.

2. In a furnace for roasting mineral sulphides in gaseous suspension, a vertically elongated, unobstructed combustion chamber, means for injecting a mixture of oxidizing gas and dried, comminuted mineral sulphide particles into the upper part of the combustion chamber, at least one collecting hearth below said combustion chamber, an outlet for roasted ore particles and an outlet for hot combustion gases from the collecting hearth, at least one drying hearth below the collecting hearth for drying the combustion chamber feed material, conduit means extending from the combustion chamber to a drying chamber defined by the collecting hearth and the drying hearth, an inlet for moist sulphide particles to the drying hearth, an outlet for dried sulphide particles from the drying hearth, an outlet for gases from the drying chamber, means for conveying dried sulphide particles from the drying chamber to the combustion chamber, a hollow rotatable shaft extending from a point below the furnace to terminate above but adjacent to the uppermost collecting hearth, rabble arms carried by said shaft, rabbles carried by said arms adapted to move on said hearths, and means for feeding a coolant through said shaft and rabble arms.

3. In a furnace for roasting mineral sulphides in gaseous suspension, a vertically elongated, unobstructed combustion chamber, means for injecting a mixture of oxidizing gas and comminuted mineral sulphide particles into the upper part of the combustion chamber, at least one collecting hearth below the combustion chamber, an outlet for roasted ore particles and an outlet for hot combustion gases from the collecting hearth, at least one drying hearth below the collecting hearth for drying the combustion chamber feed material, a drying chamber defined by the collecting hearth and the drying hearth, means for feeding moist mineral sulphide particles to the drying hearth, conduit means extending from the combustion chamber to the drying chamber, an outlet for dried sulphide particles from the drying hearth, means for conveying dried sulphide particles from the drying chamber to the

5
8
combustion chamber, conduit means for returning gas from the drying chamber to the combustion chamber, a rotatable shaft extending from a point below the furnace to terminate a short distance above the uppermost collecting hearth, rabble arms carried by said shaft, and rabbles carried by said arms adapted to move on said hearths.

4. In a furnace for roasting mineral sulphides in gaseous suspension, a vertically elongated, unobstructed combustion chamber, means for injecting a mixture of oxidizing gas and comminuted mineral sulphide particles into the upper part of the combustion chamber, at least one collecting hearth below the combustion chamber, an outlet for roasted ore particles from the collecting hearth, a separate outlet for hot combustion gases adjacent to the collecting hearth, a drying hearth below the collecting hearth, a drying chamber defined by the collecting hearth and the drying hearth, means for feeding moist sulphide ore particles to the drying hearth, conduit means extending from the combustion chamber to the drying chamber, an outlet from the drying hearth for dried sulphide particles, means communicating with the last mentioned outlet for pulverizing said dried sulphide particles, means for advancing the dried comminuted sulphide particles to the combustion chamber, and conduit means for mixing an oxidizing gas with gas from the drying chamber for admixture with the dried sulphide particles, a rotatable shaft extending from a point below the furnace to terminate a short distance above the uppermost collecting hearth, rabble arms carried by said shaft, and rabbles carried by said arms adapted to move on said hearths.
